CLIFFORD DOMMETT SHELDON, OF LONDON, ENGLAND

PAPER PULP BEATING MACHINE, HOLLANDER, REFINER, AND THE LIKE

Application filed December 3, 1929, Serial No. 411,341, and in Great Britain December 3, 1928.

This invention relates to machines employed for beating, dividing or reducing fibrous materials used in the manufacture of paper, cardboard and the like.

The types of machine to which this invention refers embody essentially a revolute member provided with blades, ribs or cutting edges, and a block or "plate" or in some cases a casing similarly furnished with blades, ribs or cutting edges co-operating with those on the revolute member to beat, triturate, divide or reduce the material which is caused to pass between them. In the case of beaters or "hollanders", sometimes termed "rag engines", the revolute member usually takes the form of a cylindrical drum with the blades or ribs disposed longitudinally around its peripheral surface, the block or "plate" being mounted closely adjacent said peripheral surface, and means usually being provided for relative adjustment to enable the gap between the "plate" and the drum to be varied.

In the case of "refiners" the revolute member is usually of truncated conical form and revolves inside a conical casing the internal surface of which is provided with the cutting blades or ribs co-operating with those on the revolute member, relative adjustment being obtained by moving either the revolute member or the casing axially.

Now the effectiveness of all these machines is improved if the co-operating cutting surfaces possess a certain amount of automatic relative adjustability to deal with varying thickness density or resistance of the material passing between them, and with this object in view it has already been proposed to mount the block or "plate" on arms or brackets turning about pivots off-set from the "plate" in suchwise that the latter can move bodily towards and away from the periphery of the drum, the bearing pressure being regulated by springs or counterbalance weights. I have found however that an improved effect is obtained by mounting the "plate" so that it is capable of an automatic rocking movement in addition to the provision for bodily adjustment with relation to the drum or revolute member. This automatic rock-

ing movement enables thickened or hardened lumps of material which would otherwise be liable to strip the teeth either of the drum or the plate to pass harmlessly between the drum and the plate, while the efficiency of the machine in breaking down the material is not adversely affected.

According to the present invention therefore, in machines of the type referred to, the "plate" is mounted so as to be capable of rocking movement about an axis or axes lying within the angle subtended by the "plate" at the axis of the drum or revolute member, and substantially parallel with the working surface of said drum or revolute member. The location of the axis or axes may vary according to the effect which it is desired to obtain. The "plate" may for instance be pivoted to rock about an axis at right angles to a radius passing through the centre of the "plate" so that the latter rocks equally in both directions or the axis may be off-set in either side of this radius so long as it is within the area defined above.

Further, the "plate" may be pivoted directly to some fixed part of the machine, or any convenient system of links or levers may be employed provided always that the virtual axis about which the "plate" rocks is within the area defined above.

Springs or flexible material may be arranged on one or both sides of or/and underneath the "plate" to cushion or restrict its movement, and bodily adjustment of the "plate" is provided for in the known or any suitable manner, to enable the gap to be adjusted.

The above description is concerned more particularly with "hollanders" or other types of beaters in which a single "plate" is employed, but if desired I may employ a plurality of such "plates" arranged and mounted according to the present invention in any appropriate positions around the circumference of the drum. Such a construction may also be employed in the "refiners" above referred to in which case the external casing co-operating with the conical drum may be made up of or support a number of separate

"plates" each or any desired number of which are mounted to rock in accordance with the present invention.

In order that the present invention may be readily understood and carried into practice several forms of construction embodying the same will now be described with reference to the accompanying drawings in which:—

Fig. 1 is a longitudinal section of a known type of beating machine showing one way of mounting the "plate" in accordance with this invention.

Fig. 2 is a longitudinal section of another type of beating machine in which the "plate" is mounted below the drum.

Figs. 3, 4 and 5 are detail views showing alternative methods of mounting the "plate".

Fig. 6 is longitudinal section of a "refiner" showing one application of the present invention thereto, and

Fig. 7 is a cross sectional view on the line 7—7 Fig. 6, both Figs. 6 and 7 being to a large extent diagrammatic in character.

Referring more particularly to Fig. 1:—
Mounted in the known manner in the fixed frame of the machine is a rotatable drum A turning about an axis X and provided, also in the known way, with a longitudinally disposed cutting blades B which although shown in detail over a part only of the periphery of the drum, extend over the whole peripheral surface thereof. Co-operating with these blades B is a set of blades hereinafter referred to as the "plate" C secured in a carrier C¹. The carrier and "plate" are pivotally and freely supported at D in the lower ends of a pair of links E which are pivoted at their upper ends F to the fixed frame of the machine.

The adjustment of the "plate" C in relation to the blades B is effected by means of the device shown in broken lines in Fig. 1. This comprises a screw-threaded arm G pivotally attached to the back of the carrier C¹ and provided with a member G¹ positioned on the arm G by nuts G². The member G¹ is keyed to a cross shaft G³ rockingly mounted in the frame of the machine and connected by a lever G⁴, a rod G⁵ and a crank G⁶ to a beam G⁷ rockingly mounted at G⁸ in the frame of the machine.

The beam G⁷ is furnished with rack teeth along which a weight G⁹ can be moved by a pinion and handwheel G¹⁰ to vary the load on the "plate" C.

Since Fig. 1 is a longitudinal sectional view of the machine, these adjusting means are shown in broken lines, to indicate their position and arrangement but they should be understood to be on the side of the machine which has been sectioned away i. e. the side in which the drum etc. are located.

It will be observed that the pivots F permit of bodily adjustment of the "plate" C and carrier C¹ towards and away from the

periphery of the drum A while the pivots D permit the "plate" to rock about an axis which is within the angle Y—X—Z subtended by the "plate" C at the axis X of the drum so that the "plate" may rock relatively to the blades B to adjust itself to some extent to variations in the thickness or density and resistance of the material passing through and control the relative pressures applied at different areas in the breadth of the "plate", depending on the position of the axis about which the "plate" rocks. In the example shown, rubber or the like resilient blocks H are provided at each end of the "plate" C to give a cushioning effect, but these are not essential and may be dispensed with if desired.

The machine being of a known type, a short description of its operation will suffice.

The fibrous material in a wet pulpy state passes up between the cutting blades B and C and falls over a weir J passing thence in the direction of the arrows around the inclined trough K at the back of the machine remote from the observer and finally arriving back at the drum A, the pulp being kept in continuous motion until it is reduced or beaten to the desired degree.

In Fig. 2, a somewhat different type of machine is shown. The pulp in this case travels round the trough in the direction indicated by the arrows and passes between the blades B and the "plate" C supported in a carrier C² which is rockingly mounted at L in the angle subtended by the "plate" C at the axis X of the drum. In this case also rubber or the like resilient blocks H are provided at each end of the "plate" C. Bodily adjustment of the "plate" C in relation to the drum A is provided by known means (not shown) the "plate" and carrier moving radially to the drum A in guides, or the drum being adjustable relatively to the "plate" in the known manner.

Figs. 3, 4 and 5 show alternative methods of mounting applicable to the type of machine shown in Fig. 1.

In Fig. 3 the "plate" C is mounted in a rubber or the like resilient support M carried on a plate M¹ which in turn is pivoted at M² in the carrier N. The latter is pivoted at O to the fixed frame of the machine to allow for bodily adjustment of the carrier N towards and away from the drum A.

In Fig. 4 the blades C^x are secured to a plate P mounted in the carrier N against compression springs Q, rubber or the like blocks R being provided at each end of the set of blades C^x. The carrier N is pivoted at C to the fixed frame of the machine as in Fig. 3.

In Fig. 5 rocking movement of the blades C^x is provided for by mounting them on a curved plate S lying in a similarly curved recess in the carrier N, the resilient cushions R

being arranged at each end of the set of blades C* as before to allow sliding motion of the plate S in the recess.

It will be observed that in all cases the arrangement is such that the "plate" is mounted to rock about an axis which is within the angle Y—X—Z subtended by the "plate" at the axis of the drum thereby providing for automatic adjustment of the relative pressures of different parts of the "plate" on the material passing through.

Referring now to Figs. 6 and 7 which illustrate one application of the present invention to a "refiner" of a known type. This machine comprises a truncated conical casing 10 into one end 11 of which the pulp or the like is fed. Mounted on a shaft 12 within the casing is a revolute member 13 of truncated conical form provided over the whole 20 of its surface with blades, ribs or cutting elements 14. Co-operating with these elements 14 is a series of "plates" 15 consisting of blades, ribs or the like secured in carriers 16 disposed around the revolute member 13 25 and pivoted at 16^a to the casing 10, the pivot in each case lying within an angle Y—X—Z subtended by the respective "plate" at the axis of the revolute member 13, thus providing in the case of each "plate" for automatic adjustment of the relative pressures 30 of different parts of the "plate" on the material passing through.

In a "refiner" of this type, the material entering at 11 passes lengthwise through the casing between the blades or like elements 14 and the "plates" 15 and is delivered through aperture 17 in the other end of the casing. The shaft 12 is driven by the belt and pulley 18, and relative adjustment of the blades 14 40 and the "plate" 15 is provided in the known manner by moving either the revolute member 13 or the casing 10 axially. As these adjusting means are well known in this type of machine, they are not shown on the drawings. Although the axes of the pivots 16^a about which the "plates" 15 rock are shown as located on radii passing through the centres of the "plates" 15, the said axes may be otherwise located so long as they lie within 50 the angle Y—X—Z for each "plate".

Although the beating, cutting or reducing members have been designated in the foregoing description and the appended claims as blades, this latter expression is to be understood as including ribs, corrugations or any other devices now used in machines of this type, or suitable for the purpose in view.

What I claim is:—

1. In a pulp beating engine, the combination of a grinding drum revolubly mounted in fixed bearings, a blade carrying plate co-operating with said drum and mounted to rock freely about an axis parallel to the working surface of the said drum, said axis lying within the angle subtended by the working

face of the plate at the axis of the drum, and means for moving the plate bodily towards and away from the drum.

2. In a pulp beating engine, the combination of a grinding drum revolubly mounted in fixed bearings, a blade carrying plate co-operating with said drum, a movable carrier for the plate, links swingingly mounted to the fixed frame of the machine and supporting the said carrier pivotally about an axis 70 parallel to the working surface of the drum, said axis lying within the angle subtended by the working face of the plate at the axis of the drum, and means for moving the said carrier bodily towards and away from the 80 said drum.

3. In a pulp beating engine, the combination of a grinding drum revolubly mounted in fixed bearings, a blade carrying plate co-operating therewith, a movable carrier for 85 the plate, links swingingly mounted in the fixed frame of the machine and supporting the said carrier pivotally about an axis parallel to the working surface of the drum, said axis lying within the angle subtended by the 90 working face of the plate at the axis of the drum, cushioning means between the carrier and the ends of the plate, and means for moving the carrier bodily towards and away from the 95 drum.

4. In a pulp beating engine the combination of a grinding drum revolubly mounted in fixed bearings, a blade carrying plate co-operating therewith, and situated below the said drum, a movable carrier for the plate 100 rockably mounted about an axis parallel to the working surface of the drum, said axis lying within the angle subtended by the working face of the plate at the center of the drum, means for moving the carrier bodily 105 towards and away from the drum and damping means for cushioning the rocking movement of the carrier.

5. In a pulp beating engine, the combination of a grinding drum revolubly mounted 110 in movable bearings, a co-operating blade carrying plate located below the drum and mounted in fixed bearings so as to rock about an axis parallel to the working surface of the drum, said axis lying within the angle 115 subtended by the working face of the plate at the axis of the drum, resilient means for cushioning the rocking movement of the plate and means for moving the bearings of the drum towards and away from the plate.

6. In a pulp beating engine, the combination of a grinding drum revolubly mounted in fixed bearings, a co-operating blade carrying plate, a carrier for the plate swingingly mounted in the fixed frame of the machine so 125 as to allow the plate to move towards and away from the drum and resilient and cushioning means between the carrier and the plate allowing the plate to rock relatively to the carrier about a virtual axis parallel to 130

the working surface of the drum, said axis lying within the angle subtended by the working face of the plate at the axis of the drum.

7. In a pulp beating engine, the combination of a grinding drum revolvably mounted in fixed bearings, a co-operating blade carrying plate, a carrier for the plate swingingly mounted in the fixed frame of the machine so as to allow the plate to move bodily towards or away from the drum, a plate supporting member pivotally mounted in the carrier about an axis parallel to the working surface of the drum, said axis lying within the angle subtended by the working face of the plate, at the axis of the drum and resilient and cushioning means carried by the plate supporting member and supporting the plate.

8. In a refiner for reducing fibrous materials for the manufacture of paper, cardboard, and the like, the combination of a truncated conical casing adapted for the entry of the material to be treated at one end thereof and the discharge of the material at the other end thereof, a truncated conical grinding drum revolvably mounted in bearings in the ends of the casing and arranged to have some degree of axial movement relatively to the casing, a plurality of co-operating blade carrying plates surrounding the drum and carriers for the plates rockably mounted in the casing about axes parallel to the working surface of the drum, said axes lying within the angles subtended by the working faces of the respective plates at the axis of the drum.

9. A refiner in accordance with claim 8 and including cushioning means interposed between the plates and their respective carriers.

40 CLIFFORD DOMMETT SHELDON.
